UNITED STATES PATENT OFFICE

JOHN T. ROBINSON, OF BOSTON, MASSACHUSETTS, ASSIGNOR TO JOHN T. ROBINSON COMPANY, OF BOSTON, MASSACHUSETTS, A CORPORATION OF MASSACHUSETTS

ROTARY CREEASING MACHINE

Application filed May 22, 1929. Serial No. 365,161.

This invention relates to machines for creasing cardboard and similar stock in the preparation of blanks which are subsequently folded to make boxes.

5 Machines of this general type usually comprise a frame in which a bar is rotatably mounted carrying a plurality of creasing and scoring units. Each of the creasing units includes a creasing wheel adapted to 55 cooperate with a creasing roll and each of the scoring units includes a sharp cutter cooperating with a hardened ring to separate the blanks. The bar carrying the creasing and scoring units is provided with 60 10 a reversing lever so that it may be turned from its normal operative position to an inverted position in order to adjust the position of the creasing and scoring units or to replace the same. Stock, such as sheet card- 65 15 board, is passed between the creasing wheels and the cooperating creasing rolls to crease the same and is separated into blanks at the same time by the scoring units. It has been common practice to lock the bar carrying the creasing and scoring units by a 70 20 pin movable by a latch on the reversing lever into openings in a segment on the frame of the machine.

This method of locking the bar is usually 75 30 satisfactory where the machine is employed solely for scoring the stock. On the other hand when the machine is employed for creasing the stock the strain set up is many times as great and the customary method 80 35 of locking the bar has been found unsatisfactory on account of the tendency of the bar to twist or move due to the wear or poor fit of the parts. As a result perfect creasing of the stock could not be accomplished after the machine had been in use 85 40 a few months.

It is an object of the present invention to 90 45 overcome this difficulty and provide means for locking the bar carrying the creasing units so that perfect creasing can be obtained during long periods of use of the machine.

In accordance with the invention the usual 95 50 locking pin described may be employed for locating the bar carrying the creasing units

in its normal operative or inverted position and a separate additional locking mechanism is provided for holding the bar against movement in the direction of movement of the stock through the machine.

Before explaining in detail the present invention, it is to be understood that the invention is not limited in its application to the details of construction and arrangement of parts illustrated in the accompanying 55 60 drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended as considered in view of the prior 65 70 art and the requirements thereof.

The invention will be more clearly understood from the following description in conjunction with the accompanying drawings, in which:

Fig. 1 is a fragmentary plan view of a 75 70 creasing machine embodying the invention;

Fig. 2 is a sectional view taken upon the line 2—2 of Fig. 1; and

Fig. 3 is a detail view of the locking mechanism of the invention in an inoperative 80 85 position.

The machine illustrated comprises a bar 9 having trunnions 11 mounted in bearings in uprights 12 so that it may be turned by a reversing lever 13. A plurality of creasing 85 90 devices 15 are adjustably mounted upon the slide 9 as by set screws 16 and each is adapted to cooperate with a creasing roll 17 adjustably mounted upon a shaft 18 rotatably mounted in the uprights 12 and adapted to 95 100 be rotated in any suitable manner (not shown). A suitable scale 21 is secured by hinges 8 to a bar 23 extending between the uprights 12. A latch 25 is pivotally mounted upon a pin 26 extending between lugs 27 on the reversing lever 13 and is connected at its free end with a pin 28 adapted to engage either of the openings 29 or 30 upon a plate 31 suitably secured to one of the uprights 12.

The opening 29 in the plate 31 is arranged so that when it is engaged by the pin 28 the creasing devices will be located in normal operative relation to the creasing rolls 17. 5 If it is desired to adjust the position of the creasing devices on the bar 9 or to replace them by other devices, the bar 9 is moved to its inverted position by operating the latch 25 to remove the pin 28 from the opening 29 and turning the reversing lever 13 until the pin 28 engages the opening 30 in the plate 31. When the bar 9 is located in its normal operative position, as shown in Fig. 2, stock S is passed between the creasing devices 15 and creasing rolls 17 in the direction shown by the arrow. 10 15

In order that there may be no movement of the bar 9 during the creasing operation which will affect the character thereof suitable mechanism is provided in accordance with the invention for locking the bar 9 against movement in the direction of movement of the stock. For this purpose a block 35 is suitably secured on each of the up- 20 rights 12, as by screws 36, at a point spaced laterally from the bar 9. Preferably, the edge 37 of the block 35 adjacent the bar 9 is tapered. A bracket 40 is suitably secured near each end of the bar 9 as by screws 41. 25 30 and each is provided with a lug 42 having an opening forming a bearing for a shaft 44 extending parallel to the bar 9 and having fast thereon a suitable operating lever 45. Fixed upon the shaft 44 adjacent each end 35 thereof is an arm 10 each of which is pivotally connected at one end with one end of a link 47 the other end of each of which is pivotally connected to a wedge block 48 movable on a bearing surface 4 on the bracket 40 into and out of engagement with the surface 37 on one of the blocks 35. Preferably, each block 48 is provided with an upwardly extending guide rod 5 movable in 40 guide openings formed in a lug 6 on the bracket 40. The surface 7 of each of the blocks 48 adjacent the blocks 35 may be tapered to cooperate with the tapered surface 37 on the latter. 45

When it is desired to lock the bar 9 in its 50 normal operative position, the lever 13 is moved until the pin 28 engages the opening 29 in the plate 31, thus locating the bar 9 in its operative position. The operating lever 45 then is moved from the position shown in Fig. 3 to that shown in Fig. 2, thereby turning the shaft 44 and causing the blocks 48 to move along the bracket 40 on the bar 9 into engagement with the blocks 35. The cooperating tapered surfaces upon 55 the blocks 48 and 35 make it possible to take up any play in the bar 9 caused by wear of the parts thereof or of the locating pin 28. If it is desired to move the bar 9 to its inverted position, the lever 45 is turned from the position shown in Fig. 2 to that shown 60 65

in Fig. 3, thereby moving the blocks 48 out of engagement with the blocks 35 and permitting the bar 9 to be moved by means of the reversing lever 13 to its inverted position. It will be noted that when the blocks 48 are either in engagement with the blocks 35 or moved out of engagement therewith, the lever 45 is off center or inclined to a vertical plane through the shaft 44 and, therefore, exerts its weight to maintain the blocks 48 in the position to which they have been moved. 70 75

What I claim is:

1. In a creasing machine, the combination 80 of a frame, a bar rotatably mounted in said frame and adapted to carry creasing devices, means for moving said bar to normal or inverted position, and means for locking said bar in one of said positions including a block rigidly connected to said frame 85 in spaced relation to said bar, and a movable wedge adapted to be inserted between said block and bar.

2. In a creasing machine, the combination 90 of a frame, a bar rotatably mounted in said frame and adapted to carry creasing devices, means for moving said bar to normal or inverted position, blocks spaced longitudinally and laterally relative to said bar and rigidly connected to said frame, means for locking said bar in one of said positions including movable wedges insertable between said blocks and bar, and means for simultaneously moving said wedges into and out of locking position. 95

3. In a creasing machine, the combination 100 of a frame, a bar rotatably mounted in said frame and adapted to carry creasing devices, means for moving said bar to normal or inverted position, blocks spaced longitudinally and laterally relative to said bar and rigidly connected to said frame, means for locking said bar in one of said positions including movable wedges insertable between said blocks and bar, and means for simultaneously moving said wedges into and out of locking position, said blocks and wedges having cooperating tapered surfaces. 105 110

4. In a creasing machine, the combination 115 of a frame, a bar rotatably mounted in said frame and adapted to carry creasing devices, means for moving said bar to normal or inverted position, blocks spaced longitudinally and laterally relative to said bar and rigidly connected to said frame, means for locking said bar in one of said positions including movable wedges insertable between said blocks and bar, guides for said wedges, and means for simultaneously moving said wedges into and out of locking position. 120 125

5. In a creasing machine, the combination 130 of a frame, a bar rotatably mounted in said frame and adapted to carry creasing devices, means for moving said bar to normal

or inverted position, blocks spaced longitudinally and laterally relative to said bar and rigidly connected to said frame, means for locking said bar in one of said positions including movable wedges insertable between said blocks and bar, a shaft rotatably mounted in said frame, a bell crank lever fixed to said shaft above each of said wedges, and a link connecting the end of each of said levers with one of said wedges.

5 10 In testimony whereof I affix my signature.
JOHN T. ROBINSON.
